(57) CLAIM

The ornamental design for a display screen with icon, as shown and described.

DESCRIPTION

FIG. 1 is a front view of a display screen with icon; and, FIG. 2 is a front view of another display screen with icon. The broken lines shown surrounding the display screen with icon are for the purpose of illustrating an article of manufacture on which the display screen with icon is provided; the broken lines shown within the bounds of the display screen with icon are for the purpose of illustrating portions of the article; the broken lines form no part of the claimed design.

1 Claim, 2 Drawing SheetsFIG.1
